US0D1077663S

(12) **United States Design Patent** (10) **Patent No.:** **US D1,077,663 S**
(45) **Date of Patent:** **** Jun. 3, 2025**

(54) **DOORBELL**

(71) Applicant: **Dongguan Yu Aoran electronic Technology Co., LTD**, Dongguan (CN)

(72) Inventor: **Mang Zhang**, Zaoyang (CN)

(73) Assignee: **Dongguan Yu Aoran electronic Technology Co., LTD**, Dongguan (CN)

(**) Term: **15 Years**

(21) Appl. No.: **29/981,720**

(22) Filed: **Jan. 2, 2025**

(51) LOC (15) Cl. **10-05**

(52) U.S. Cl. **USPC .....** **D10/118.2**

(58) **Field of Classification Search**

(57) **CLAIM**

The ornamental design for a doorbell, as shown and described.

DESCRIPTION

FIG. 1 is a front perspective view of a doorbell, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1.

The broken lines in the drawings illustrate the portions of the doorbell, which form no part of the claimed design.

The dash-dot-dash broken lines encircling the enlarged views are for annotative purposes only and form no part of the claim thereof.

1 Claim, 9 Drawing Sheets
